FEEDING AND ALIGNING DEVICE

Beulah Louise Henry, New York, N. Y.

Application August 9, 1937, Serial No. 156,079

19 Claims. (CL 197—127)

This invention relates to typewriting machines, and more especially to an improved means for feeding superposed sheets in strip or web form in aligned or properly collated relation.

It is an object of the present invention, as of the invention set forth and claimed in my copending application Serial No. 134,467, filed April 2, 1937, to provide a writing machine especially adapted for use with a web or continuous series of collated and superposed sheets in which the need for pre-formed marginal holes is eliminated and in which the collated forms are positively fed relative to the printing line in alignment and in register.

It is a further object of the present invention to provide a highly efficient means for assuring positively the same extent of lineal travel of both inner and outer webs or strips over the platen roller regardless of the number of strips superposed and regardless of the lineal extent of said superposed strips.

In achieving these objects there is provided as a feature of the invention a means for positively feeding the superposed strips in a flat path at the same lineal speed as the platen roller.

Another feature of the invention resides in providing a pin feeding means operable by the platen shifting means to pierce the superposed strips while the latter are guided in a flat path and to advance the same concurrently with and at the same lineal speed as the platen roller.

A further feature of the invention resides in providing both a means for normally locking the superposed sheets relative to each other on the platen roller and a pin means for piercing the sheets and advancing the same in a flat path concurrently with the rotation of the platen. A complementary feature resides in providing a means operable upon actuation of the platen rotating means for moving said locking means to an inoperative position and for subsequently advancing the pin feeding means.

Another feature of the invention resides in utilizing a clutch means for connecting the platen roller with the feeding pin to positively and concurrently advance the latter and the platen roller upon actuation of the platen shifting lever.

A further feature of the invention resides in providing a means adapted to positively advance superposed strips equal lineal extents in aligned relation in a flat path conjointly with the rotation of the platen roller, said means being adjustable to cooperate with strips of divers widths.

Another feature of the invention consists in providing a feeding means operable to positively advance the superposed strips toward the platen

roller in aligned relation conjointly with the rotation of the roller and in also providing a means for automatically conditioning the usual paper release mechanism upon the actuation of the platen shifting means.

A further feature of the invention resides in providing a pin feeding means movable from an inoperative position to pierce the superposed strips and subsequently movable to advance the sheets upon a flat guide member concurrently with the rotation of the platen roller.

Other objects and features in the invention will hereinafter appear.

In the drawings:

Figure 1 is a top view of a conventional typewriter carriage and platen showing one form of the invention associated therewith.

Fig. 1A is a detail view of the feeding pin carrier.

Fig. 2 is a view taken on the line 2—2 of Fig. 1 looking in the direction of the arrows.

Fig. 3 is a view partially in section showing the clutch means for locking the platen relative to the feeding pin actuating gears.

Fig. 4 is a top view similar to Fig. 1 with the platen omitted and showing the modified form of the invention.

Fig. 5 is a sectional view taken on the line 5—5 of Fig. 4.

Fig. 6 is an end view looking toward the right in Fig. 4 with a portion of the carriage omitted to enable a clearer illustration.

Fig. 7 is a top view similar to Fig. 4 showing another modified form of the invention.

Fig. 8 is a view taken on the line 8—8 of Fig. 7.

Fig. 9 is a fragmentary exploded detail view showing the feeding pin control means.

Fig. 9A is a detail view of the feeding pin showing the relation of the pin carrier and control bar in Figs. 7 through 9.

Fig. 10 is a detail of a gripping member.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

Although the several forms of the present invention are shown applied to a conventional typewriter of the form used for correspondence it will be understood that they are equally applicable

on tabulating, bookkeeping, accounting and other machines where it is desirable to maintain and feed collated sheets or strips in register.

Referring more particularly to the drawings 5 and first to Figs. 1 through 3, there is shown for the purpose of illustration side frames 20 and 21 of a conventional typewriter carriage supporting in recesses 22 and 23 respectively in the upper faces thereof a rotatable shaft 24 carrying a 10 platen roller 25 of rubber or the like upon which superposed collated strips or sheets of record material, such for example as original sheet 26 and duplicate sheet 27 with a carbon paper 28 therebetween, may be typed. Fingers 29 and 30 15 secured to the frames 20 and 21 by screws 31 serve in a well-known manner to confine the shaft 24 in the recesses 22 and 23 for rotation therein. Conventional turning knobs 32 are shown at both ends of the shaft 24 for rotating the platen 25.

20 As is also conventional, there is disclosed a platen shifting lever 33, preferably in the form of a bell crank, pivotally carried on an extension 34 on the side frame 20 which through a suitable linkage 35 is connected with a pawl 36 for engagement with a ratchet wheel 37 fixed on the shaft 24 to impart a step-by-step rotary movement to the platen 25 upon actuation of the platen shifting lever 33 in a counterclockwise direction. Any suitable spring means may be provided to return the shifting lever 33 in a clockwise direction after the completion of the platen 30 rotating movement.

In the present invention, Figs. 1 and 3, however, it is to be particularly noted that a means 38 is provided for engaging the superposed collated strips and positively feeding the same on a flat table or guide section 39 prior to their passage to the platen roller 25.

The table section 39, as shown, is disposed at an 40 angle at the rear of the platen roller 25 to guide the superposed strips downwardly to pass under the platen roller in the conventional manner. Pivotal supports for the table section are provided by pins 40 in upstanding rigid supporting 45 arms 41 and 42 on the side frames 20 and 21 respectively, which extend through ears 43 on the table section. The pins 40 likewise serve as a pivotal mounting for a paper lock bail 44 comprising arms 45 and 46 which rotatably carry therebetween a shaft 47 on which are provided 50 usual paper lock rollers 48 adapted to rest upon the platen 25. Springs 49, connected to the supporting arms 41 and 42 and to the arms 45 and 46, serve to yieldingly maintain the bail 44 in a 55 lowered position.

For further supporting the table section 39 and for maintaining the same in adjusted angular positions, rearwardly extending ears 50 are provided at either side thereof and are formed with 60 arcuate slots 51 to receive holding screws 52 in the side frames 20 and 21.

The advantageous feeding means 38 includes a pair of feeding pins 53 spaced transversely of the table section and mounted for movement 65 toward the table or guide section 39 to pierce the superposed strips, and for subsequent movement to positively advance the sheets on the flat guide section concurrently with the rotation of the platen.

70 For thus mounting the feeding pins there is provided a U-shaped feed control bail 54 having a transverse control bar 55 with a slot 56 formed therein, and having forwardly extending rack bars 57 and 58 at either side thereof cooperable with gears 59 and 60 on the platen shaft 24 at

either end of the platen roller 25. A rod 61 extending between the side frames 20 and 21 and passing through slots 62 in the rack bars 57 and 58 provides a pivotal mounting for the feed control bail. Springs 63 serve to normally yieldingly 5 maintain the control bail 54 in the upper and retracted position shown in Fig. 2 with the rod 61 engaging the lower ends of the slots 62.

Links 64 and 65, having apertures 66 at one end to receive cams 67 on the paper lock bail 10 shaft 47 for a purpose to be presently described in detail, and having pivotal connections at the other end with ears 68 on the slotted control bar 55, complete the mounting of the control bail 54.

As shown, the feeding pins 53 are respectively 15 secured in carrier blocks 69, see Figs. 1 and 1A in particular, slidably positioned in the slot 56 in the control bar 55 and held therein by screws 70, flanged cap pieces 71 and wing nuts 72. This construction is advantageous in that either or 20 both of the feeding pins may be adjusted laterally relative to each other on the control bar to cooperate with the margins of divers width sheets or strips by merely loosening the wing nuts 72.

As shown most clearly in Fig. 3, the gears 59 25 and 60 are normally free to rotate upon the platen shaft 24, while the platen is affixed thereto by keys 73 in the shaft 24 extending into a keyway 24' in the platen. Of particular importance, however, it is to be noted that these gears are 30 each mounted between a pair of friction discs 74 in such a way that when the shaft 24 is moved slightly toward the left the gears are each locked relative to the platen roller to rotate therewith.

This clutch means 75 for locking and unlocking 35 the gears 59 and 60 relative to the platen 25 is achieved by providing a collar 76 affixed to the shaft at the right of the gear 60 and by affixing the ratchet wheel 37 to the shaft 24 at the left of gear 59 through a pin and slot connection 77 40 which while locking the ratchet wheel to the shaft for rotation therewith permits a slight movement thereof longitudinally of the shaft.

With this construction, therefore, when the shifting lever 33 is actuated in a counterclockwise direction to rotate the platen 25, the platen shaft 24 through a spring finger connection 78 with the shifting lever 33 is moved to the left causing the collar 76 to urge the gears 59 and 60 and platen 25 to the left and thus lock the gears 50 between the friction discs 74 as the ratchet wheel 37 is pressed against the side frame 20.

This locking of the gears 59 and 60 relative to the platen 25 causes the gears to rotate therewith and move the rack bars 57 and 58 and the associated feed pins 53 forwardly in the direction of feed. To insure that the movement of the feed pins will be exactly the same as that of the periphery of the platen roller 25 the pitched diameter of the gears 59 and 60 is made exactly 60 the same as the outside diameter of the platen roller.

The advantageous spring finger connection 78 between the shifting lever 33 and the platen shaft 24 is preferably achieved by means of a flat 65 spring 79 secured to the shaft by means of a collar section 80 and to a lower extension 81 of the pivot stud 82 of the shifting lever 33 by a slotted connection 83.

For moving the feeding pins 53 from the inoperative position shown, to pierce the collated sheets on the flat table section 39, there is provided on the shifting lever 33 an integral or an affixed extension 84 with a pin 85 engaging in a slot 86 in the end of a spring strip 87 having a 75

clamping connection 88 with the rotatably carried shaft 47 of the paper lock ball 46.

With this construction, upon initial movement of the shifting lever 33 and before the pawl 36 engages the ratchet wheel 37 the shaft 47 is partially rotated to cause the cams 67 through the links 64 and 65 to pivot the control ball 54 on the pins 61 and thus force the feeding pins 53 toward the table section to pierce the collated

10 sheets thereon.

Preferably, there is also associated with the shaft 47 a pair of fingers 89 carrying locking pins 90. The relation of the fingers 89 and the shaft 47 is such that the locking pins 90 are normally maintained in an operative position 15 piercing the collated sheets and locking the same relative to each other and to the platen 25. However, when the shaft 47 is rotated causing the cams 67 to move the feeding pins 53 into operative relation with the collated sheets on the table sections, the fingers 89 are concurrently moved away from the platen roller and out of the collated sheets.

Thumb screws 81 in the fingers 89 and entering a slot 92 in the shaft 47 serve to effectively lock the fingers relative to the shaft and at the same time permit an adjustment thereof longitudinally of the shaft to cooperate with the margins of divers width strips. A flat spring 46' secured to the arm 46 and entering a suitable slot 47' in the rod 47 yieldingly urges the pins 90 through the collated sheets and maintains the slot 86 in register with the pin 85 as the bail 44 is swung from the raised inoperative position to the lowered operative position.

In the operation of the device the collated sheets are first inserted to pass downwardly over the table section 39 and thence under the platen roller 25 and upwardly in front of the same. The paper lock ball 46 is then moved downwardly so that paper lock rollers 48 rest upon the collated sheets on the platen roller 25 and the locking pins 90 pierce the sheets to lock the same relative to each other and to the platen. The pin 85 and slot 86 connection between shifting lever 33 and the shaft 47 permits this movement of the paper lock ball 46. A line of printing may then be applied to the collated sheets in the well-known manner.

Thence, when it is desired to advance the sheets to bring a new portion thereof opposite the printing line the shifting lever is actuated in the usual manner. Upon an initial movement of the shifting lever and before the shifting pawl 36 engages the ratchet wheel 37, the feeding pins 53 through the operation of the cams 67 are forced from the inoperative position, shown in Fig. 2, to pierce the collated sheets on the flat table section. Concurrently the locking pins 90 are withdrawn from the sheets to free the same from each other on the platen roller. Relative movement of pins 53 and 90 may be timed in any desired way by adjustment of the cam 67 on the rod 47. Preferably the feeding pins 53 are forced through the collated sheets before the locking pins 90 are released therefrom. Also, during the initial movement of the shifting lever 33, the platen shaft 24 through the spring finger connection 78 is moved slightly to the left to take up the slack and lock the gears 59 and 60 relative to the platen 25 between the friction discs 74.

Subsequent and platen advancing movement of the shifting lever 33 causes the rotation of the platen 25 which through the locked gears 59 and 60 causes the rack bars 57 and 58 to be moved

forwardly carrying therewith the feeding pins 53 which through their piercing relation with the collated sheets advance the same on the flat table section 39.

Because the collated sheets on the table section 5 are advanced in a flat as distinguished from a curved path by the pins 53 an exactly lineal feed is given to the inner and outer sheets. And because these sheets are positively locked relative to each other this exactly equal lineal advance 10 of the sheets is carried forward when the same pass around the platen roller. This represents a distinct advantage, especially when feeding very long collated strips because there is a definite tendency of the superposed strips or sheets to 15 creep relative to each other due to the greater turning radius of the outer strips.

During a return of the platen shifting lever to its initial position, as by a conventional spring, the shaft 47 of the paper lock ball is rotated to 20 move the locking pins 90 back into piercing relation with the sheets, and through the cams 67 to withdraw the feeding pins 53 from the strips on the flat table section.

Concurrently the platen shaft 24 through the 25 spring finger connection 78 is moved slightly to the right, releasing the frictional clutch drive of the gears 59 and 60 and permitting the springs 83 to subsequently return the racks 57 and 58 and associated feed pins 53 to the initial re- 30 tracted position, shown in Fig. 2, as the gears 59 and 60 rotate freely on the platen shaft 24. The timing is preferably such that the locking pins 35 are first moved to the operative position, the feeding pins are next released from the collated sheets, and finally the clutch is released so that the rack bars and feeding pins are returned to the retracted position.

Preferably in order that the feeding pins 53 may serve most effectively to advance the collated 40 sheets a series of grooves 93 is formed in the table section extending in the direction of feed to receive the feeding pins 53 when the latter are forced through the collated sheets.

It will be readily appreciated that this form 45 of the invention may be applied to typewriters and the like now in the field having a flat table section at a considerable angle in back of the roller inexpensively and without major changes.

In Figs. 4 through 6 another form of the invention is disclosed. It differs from the form first described primarily in the provision of a different locking pin arrangement and in the fact that it is arranged to feed superposed strips or webs relative to a flat guide member 99 which is on a substantially horizontal plane. This guide member 99 has an upper plate 100 and a lower plate 101 defining therebetween a guide passage for the collated strips as they are fed toward the platen roller 25. Ears 102 and 103 on the upper plate 100 cooperating respectively with screws 104 in the side frames and with a rod 105 extending between the side frames 20 and 21, and ears 106 and 107 on the lower plate cooperating respectively with screws 108 in the side frames 20 and 21 and in inward extensions 109 and 110 thereon, the side frames serve to maintain the guide member 99 in position.

As in Figs. 1 through 3, Figs. 4 through 6 disclose side frames 20 and 21 of a conventional 70 typewriter carriage supporting a platen roller 25 of rubber or the like. Also, as in Fig. 1 and as is conventional, there is included a shifting lever 33 for operating the pawl to engage with the ratchet wheel and impart a step-by-step rotary move- 75

ment to the platen roller 25. Likewise, there is provided a paper lock bail 44 pivotally associated with the side frames 20 and 21 by arms 45 and 46 pivotally mounted on the rigid supporting arms 41 and 42 to be swung upwardly and into a retracted position at the back of the machine. Springs 49 serve to yieldingly maintain the bail 44 in a lowered position. It is to be noted, however, that the shaft 47 carried between the arms 45 and 46 and on which are mounted the paper lock rollers 48, is connected in no way with the shifting lever 33 and is free of any locking pins.

In this modified form of the invention there is provided a control bail 111 of substantially rectangular form for supporting both feeding pins 112 and locking pins 113. Rack bars 114 and 115 forming the sides of the bail and preferably integral therewith are slidable in suitable channels 116 and 117 in inward extensions 109 and 110 on the side frames 20 and 21. The rack bars 114 and 115, as the rack bars 57 and 58 in Figs. 1 through 3, mesh with the gears 59 and 60 on the platen shaft 24. The clutch means 75 for locking the gears relative to the platen roller 25 for rotation therewith is the same as in the form first described and shown clearly in Fig. 3.

A bar 118 at the front of the control bail 111 and having a slot 119 therein supports a pair of slide blocks 120 accommodating the locking pins 113. As shown most clearly in Fig. 5 these slide blocks are provided with arcuate guide channels 121 adapted to receive heads 122 on the locking pins 113 and permit slight movement thereof with the platen.

For associating the slide blocks with the bar 118 screws 123 are inserted in portions of the blocks overlying the bar to extend through the slot 119 therein. Wing nuts 124 serve to clamp the slide blocks to the bar 118 in divers positions 40 thereon to cooperate with wide and narrow sheets or strips of paper.

The feeding pins 112 are respectively supported on a pair of inverted U-shaped carriers 125 adapted to slide both vertically and longitudinally on a control bar 126 at the rear of the control bail 111.

Vertical movement of the pair of feeding pins 112 is effected by rotating a rod 127 carried between the side frames 20 and 21 at the rear of the control bar. Movement of the rod 127 is transmitted to the respective pins 112 by flat spring fingers 128 connected at one end to the underside of collar blocks 129 slidable longitudinally on the rod 127 and held for rotation therewith by thumb screws 130 entering a slot 131 therein. At the other end the flat springs 128 enter suitable slots 132 in the inverted U-shaped carriers. Thus, when the rod 127 is rotated in a clockwise direction the feeding pins 112 through 60 the flat springs 128 are forced upwardly to pierce the collated strips. Upward movement of the carriers 125 and pins 112 is limited by the springs 128 engaging the bottom of the control bar 126 of the control bail 111.

For rotating the rod 127 there is provided a cam 133 at the lower end of an extension 81 on the shifting lever pivot stud 82 which engages with a cam confining collar 134 on a link 135 having a pivot connection 136 with the upper end 70 of a lever 137 on the rod 127. A stop plate 138 below the cam 133 serves to maintain the link 135 and cam engaging collar 134 in operative association therewith.

The means operating the clutch means 75 to 75 lock the gears 59 and 60 for rotation with the platen

roller 25 is the same as in Figs. 1 through 3 and includes a flat spring 78 connected to the platen shaft 24 at one end, and having a connection with a slot 83 in the extension 81 on the shifting lever pivot stud 82 at the other end. Springs 139 5 serve to yieldingly maintain the control bar 111 and feeding pins 112 in the retracted rearward position shown in Figs. 5 and 6.

In the operation of this form of the invention when the shifting lever 33 is moved in the conventional manner in a counterclockwise direction, as viewed in Fig. 4, the cam 133 is initially rotated to pull the link 135 forwardly and thus partially rotate the rod 127 causing the spring fingers 128 to lift the carriers 125 and force the feeding pins 112 through the collated strips. Preferably, a series of narrow grooves 140 are formed in the upper plate 100 of the guide member 99 to receive the feeding pins as the latter are forced through the collated strips. 20

Concurrently, through the spring finger connection 78, the clutch means 75 is conditioned to lock the gears 59 and 60 for rotation with the platen.

After the feeding pins 112 have been forced through the collated sheets and the gears 59 and 60 have been locked for rotation with the platen roller 25, subsequent clockwise movement of the shifting lever 33 causes the conventional pawl and ratchet wheel mechanism to rotate the platen roller 25, whereupon the gears 59 and 60 drive the rack bars 114 and 115 simultaneously and exactly the same lineal extent as the peripheral travel of the platen to advance the feeding pins and engaged collated strips toward the platen. 35 A slot 141 in the lower plate 101 permits an uninterrupted advancing movement of the feeding pins and likewise permits adjustment thereof longitudinally of the control bar 126 to cooperate with collated strips of divers widths. 40

During this advancing travel of the rack bars 114 and 115, the associated front bar 118 is moved away from the platen in order to withdraw the pair of locking pins 113 therefrom and from the collated strips thereon. Because of the fact that there may be a slight extent of travel of the platen 25 and strips before the locking pins are entirely withdrawn, there is provided a means for permitting a small movement of the locking pins with the strips until a full release of the platen and sheets is effected. This latter means, as heretofore described, includes the arcuate guide channels 121 in the locking pin slide blocks 120. 45

Upon a completion of the advancing or feeding operation the shifting lever 33 is released and returns to its initial position under the influence of any conventional spring means. During the return movement of the shifting lever, the cam 133 through the link 135, rod 127 and spring 60 fingers 128 withdraws the feeding pins 112 from the collated strips. The clutch means 75 is then released as in the form disclosed in Figs. 1 through 3 and the gears 59 and 60 are rendered free to rotate on the platen shaft 24, whereupon the springs draw the control bail 111 to its initial retracted position. A stop 142 engageable with the front bar 118 may be provided to limit the retracting movement of the control bail 111. In this movement of the control bail the locking pins 113 are again forced into piercing relation with the strips on the platen roller to lock the same thereto. During initial release of the shifting lever 33, and prior to release of the clutch and bail for retraction, the feeding pins 112 are re- 70 75 80 85 90 95 98

turned to their initial retracted positions in readiness to again advance the strips concurrently with the platen roller 26 upon subsequent actuation of the shifting lever.

5 The form of the invention disclosed in Figs. 7 through 9 is generally similar to the forms heretofore described and illustrated in Figs. 1 through 6. It differs from those forms principally in that it provides a direct nonyielding drive 10 for both the feeding pins 144 and the locking pins 145.

The side frames, paper lock bail, platen shifting mechanism, platen roller, as well as the gears and clutch means on the platen shaft 24, may 15 be exactly the same as those shown in Figs. 1 through 6. Preferably, in this form of the invention a flat horizontal guide member 146 is provided similar to the guide member 99 disclosed 20 in Figs. 4 through 6 and comprising an upper plate 147 and a lower plate 148 defining therebetween a guide passage 149. Ears 150 and 151 on the upper plate 147 cooperating respectively with screws 152 in the side frames 20 and 21 and with a rod 153 extending between the side 25 frames, and ears 154 and 155 on the lower plate 148 cooperating respectively with screws 156 in inward extensions 157 and 158 on the side frames and with a rod 159 extending between the side frames serve to maintain the guide member in 30 position.

Referring now in detail to those features of construction in this form of the invention differing from the forms previously described, a long downwardly extending shaft 160 is provided as 35 the pivot member of the shifting lever 33, and through a crank arm 161 at the lower end thereof, is connected to a rack bar 162 which may be slidably supported in a channel 162' in an inwardly extending flange 157 on the side frame 20. A gear 163 secured to a rod 164 rotatably 40 mounted between the side frames 20 and 21 is adapted to engage with the rack bar 162 and to be moved thereby. Oscillation of this rod 164, as will presently appear, controls both locking pins 145 and feeding pins 144.

The pair of locking pins 145, as seen in Figs. 7 and 8, are respectively carried by fingers 166 on collar blocks 167 slidable longitudinally on the rod 164 to enable the locking pins to engage with the margins of divers width strips. Thumb screws 168 engageable in a suitable slot 169 in the red serve to lock the fingers 166 and associated locking pins to the rod for rotation therewith while permitting adjustment of the locking pins 55 longitudinally of the rod.

Normal retraction of the conventional shifting lever 33 to its neutral or initial and inoperative position, as by any usual spring means, causes the rack bar 162 to arcuately move the locking pins through the collated strips superposed upon the platen, and preferably into the platen a slight extent to lock the collated strips relative thereto and to each other during the typing operation. As shown, it is desirable to locate the locking pins 145 and fingers 166 below the usual type carrying head of a type bar so that there will be no interference.

The pair of feeding pins 144 are carried by a 70 modified control bail of U shape somewhat similar to the control bails in Figs. 1 through 6. As with those control bails the bail 170 in the form disclosed in Figs. 7 through 9 is controlled to force the pair of feeding pins through the collated strips, by direct mechanical (nonyielding)

means, and then to advance the feeding pins concurrently with the platen roller.

For thus controlling the bail 170 and feeding pins 144 a pair of cams 171, are mounted on the rod 164, preferably at opposite ends thereof, for rotation therewith, and are adapted to engage ears 172 and 173 on a pair of slide members 174 which may be advantageously supported in suitable channels 175 provided in inward extensions or lugs 157 and 158 on the side frames 20 and 21. A plate 176 held in place as by screws 177, may be provided to lock one of the slide members in the channel 175 in the extension 158. A like plate, omitted from Fig. 7 for purposes of a more clear illustration, may also be provided to maintain the other slide member 174 in the channel 175 on the other side frame 20.

Of particular importance the control bail 170 is formed with a crossbar 178 at the rear thereof provided with a channel 179 therein adapted to accommodate a control bar 180 which serves as a support for a pair of carriers 181 for the feeding pins 144. Extending forwardly at either side of the crossbar 178 are rack bars 182 and 183 supported together with the slide members 174 25 in the channels 175 for forward movement therein under the influence of the gears 59 and 60, controlled by the clutch members 75 (see Fig. 3). Springs 184 serve to normally maintain the control bail 170 in the retracted position shown 30 in Figs. 7 and 8.

For supporting and controlling movement of the control bar 180 in the channel 179 in the crossbar 178, the slide members 174 are provided with guide or cam channels 185 adapted to receive pins 186 extending outwardly from both ends of the control bar.

Each of the main control channels 185 preferably includes a lower substantially horizontal channel 187 adapted to maintain the control bar 40 180 and associated carriers 181 and feeding pins 144 in a lowered position relative to the crossbar 178 and guide member 146 when the shifting lever 33 is in its inoperative initial position and the slide members 174 are in the forward position shown in Fig. 7.

Each of the main control channels 185 also includes a coextensive upwardly inclined channel 188 and a long upper channel 189 adapted to respectively engage with the pins 186 to raise the control bar and then guide the same in an upper and operative position as first the slide members are moved rearwardly by the cams 171 and subsequently the control bail and associated control bar and feeding pins 144 are moved 50 forwardly by the operation of the gears 59 and 60 and rack bars 182 and 183.

To enable a proper and complete piercing of the superposed collated strips in the horizontal guide member 146 by the feeding pins 144 when 60 the latter are forced upwardly with the control bar 180, a series of grooves 190 are formed in the upper plate 147 of the guide member.

As shown most clearly in Fig. 9, each of the feeding pin carriers 181 is preferably formed in 65 two parts with a bottom plate 191 and front plate 192 connected by a pivot pin 193 passing through suitable hinge knuckles 194 and 195 thereon. These parts are so proportioned that the front plate 192, to which the feeding pin is 70 connected, fits solidly against the crossbar 178 thus preventing a rearward tilting of the feeding pin 144 as the control bail advances the same to feed the superposed collated strips forwardly toward the platen roller. However, a spring 196 75

which normally maintains the front plate 192 in an upstanding position is very weak. Hence the pin 144 may be bent forwardly so as not to drag on the strips when the control bail 170 is moving to the initial and retracted position after the completion of the strip or sheet advancing movement. A stronger spring may be provided to cause a dragging action and thereby flatten out the superposed sheets as it moves to the retracted position.

A stud 197 having a head 198, shank 199 and threaded portion 200 is provided for each of the two feeding pin carriers 181 to cooperate in maintaining the same in proper relation with the control bail 180. As shown most clearly in Fig. 9A, the head 198 of the stud rests on the top of the control bar while the shank 199 passes downwardly through a slot 201 therein to receive on the threaded portion 200 a wing nut 202 which securely locks the bottom plate 191 of the carrier against the underside of the control bar. With this construction the feeding pins may be easily adjusted to cooperate with strips of divers widths by merely loosening the wing nut 202 and sliding either one or both of the carriers 181 longitudinally of the control bar.

In the operation of this form of the invention when it is desired to advance sheets or strips one or more line spaces in the machine, the shifting lever 33 is operated in the usual manner whereupon the crank 161 through the rack bar 162 and gear 163 rotates the rod 164 in a counterclockwise direction, as viewed in Fig. 8, to withdraw the locking pin 145 from the platen roller 25 and superposed collated strips or sheets.

Concurrently the cams 171 move against the fingers 173 on the slide members 174 to push the latter toward the rear of the machine, whereupon the inclined channels 185 cooperate with the pins 186 on the control bar 180 to move the latter upwardly and force the feeding pins 144 through the collated sheets and into the grooves 190 in the upper plate of the guide member 146.

All of the above movements take place during the initial movement of the shifting lever 33 and before the conventional link 35 actuates the conventional ratchet drive for the platen roller.

During subsequent and platen rotating actuation of the shifting lever 33, the gears 59 and 60, which have been locked for rotation with platen shaft 24 by the conditioning of the clutch means 75 (see Fig. 3), are rotated to move the rack bars 182 and 183 forwardly and thus advance the feeding pins 144 to carry the superposed collated sheets forwardly a lineal extent exactly equal to the peripheral travel of the face of the platen roller. The strips are thus fed forwardly to pass under the platen and then between the conventional paper lock rollers and the platen, with exactly the same lineal advance being transmitted to each of the superposed strips whether it be an inner or an outer strip.

Upon a release of the platen shifting lever 33 after the completion of the advancing movement, it is returned to its initial position by any usual spring means. During this return movement the rack bar 162 moves forwardly to rotate the rod in a clockwise direction. This rotation of the rod causes the locking pins to pierce the superposed strips and lock the same relative to each other and to the platen and also causes the cam 171 to engage the fingers 172 on the slide members to pull the latter forwardly causing the control channel 185 to withdraw the feeding pins from the collated strips.

Concurrently, the clutch means 75 is released in the same manner as in the forms disclosed in Figs. 1 through 6, and the gears rendered free to rotate on the platen shaft 24. Springs 184 then pull the control ball 170 and associated feeding pins into the retracted and normally inoperative position shown.

A transverse slot 203 in the lower plate 148 of the guide member permits freedom of movement of the feeding pins 144 in the direction of strip feed during both the rearward and forward movement of the pins.

In the event that the feeding pins 144 are not entirely clear of the superposed strips at the beginning of the return movement of the rack bars 182 and 183 on the release of the clutch means 75, adverse fouling of the pins on the strips is prevented by the forward yield of the pin supporting plates 192 of the carriers which causes the pins 144 to ineffectively slide along the undersurface of the collated strips.

In all forms of the invention it is therefore seen that because of the positive feeding of the superposed strips on a flat guide member there is an exactly equal lineal feed given to each of the superposed sheets whether the same be an inner or outer sheet on the platen, and further that this feed is accomplished concurrently with the usual rotary feed of the platen.

If preferred the various small piercing pins 30 hereinbefore described may be replaced with gripping members 212, as shown in Fig. 10, to press the sheets together, and against slipping. However, it is less advantageous than the pins which actually pierce the paper.

As shown in Fig. 1, there may be provided with each of the forms of the invention a means controlled by the platen shifting lever for moving the usual small pressure rollers underlying the platen to a material releasing position. In the preferred embodiment illustrated, this means includes an L-shaped arm 205 with an intermediate bowed portion 206, extending between and secured to the shifting lever 33 and a usual pressure release handle 207 with which all standard typewriters are equipped.

With this construction the handle 207 is moved to release the pressure rollers during initial movement of the shifting lever 33. Subsequent and platen rotating movement of the shifting lever is permitted by the flexing of the spring arm. Return of the shifting lever moves the handle 207 to pressure locking position. Hence, while the pressure rollers are normally maintained in operative position to hold the record material beneath the platen, they are automatically moved to a releasing position to prevent a drag on the sheets record material during the platen rotating and material feeding operation. In the illustration given, the releasing handle 207 is so associated with the pressure rollers that a rearward movement thereof is required to release the pressure rollers. If the handle is such that forward movement is required to release the pressure rollers it is merely necessary to reverse the L-shaped arm, as shown in dotted lines, so that its operative axis lies on the other side of the pivotal axis of the shifting lever.

A further device for automatically moving the usual pressure rollers to a material releasing position is shown in Fig. 8. Like the pressure release control illustrated in Fig. 1, this control may be advantageously provided with each of the forms of the invention.

This modified control means, unlike the one

first described, is operable upon movement of the paper lock bail 44 to a lower and operative position. It includes a cam 208 on an arm 45 of the ball 44 which engages a projection 209 on the usual pressure release handle 207 to cause the latter to move to a pressure releasing position. Thus, when the bail 44, and also the pin means in Figs. 1 through 3, are swung to operative position the usual pressure rollers are automatically moved away from the platen to prevent any adverse drag on the material during the actuation of the pin feeding means.

Variations and modifications may be made within the scope of this invention and portions of the improvements may be used without others.

Having thus described the invention what is claimed as new is:

1. In a device of the character described the combination of a rotary platen for supporting a sheet; feeding means engageable with said sheets; a gear and rack for advancing said feeding means; a clutch associated with said gear and rack; and means for shifting said platen and for coordinately conditioning said clutch to actuate said gear and rack and thereby advance the feeding means.

2. In a device of the character described the combination of a rotary platen for supporting a sheet; gear and rack actuated feeding means engageable with said sheet; locking means engageable with said sheet; a clutch; platen shifting means; and means, operated by said platen shifting means, for rendering said locking means inoperative and said feeding means operative and for concurrently conditioning said clutch to render the gear and rack actuated feeding means operative concurrently with the platen.

3. In a device of the character described the combination of a platen for supporting superposed sheets; a pin feeding means movable from an inoperative position to pierce said sheets and then movable to positively advance said sheets in a flat plane to cause equal lineal movement of each of said superposed sheets on said platen; and a single means for moving said pin feeding means from said inoperative position to pierce said sheets and for subsequently moving said pin feeding means to advance said sheets.

4. In a device of the character described the combination of a platen roller for supporting sheets; a substantially flat guide member; feeding means movable from an inoperative position to engage said sheets while on said guide member and then movable in a substantially flat plane to advance said sheets; platen shifting means; and means for placing the feeding means in operative relation with said shifting means to effect movement of said feeding means to engage said sheets and to subsequently advance said sheets concurrently with the rotation of said platen roller.

5. In a device of the character described the combination of a rotary feeding means for a sheet; a flat feeding means for said sheet; locking means for engaging said sheet; and means for moving said locking means to an inoperative position and for subsequently and concurrently actuating said rotary and flat feeding means.

6. In a device of the character described the combination of a platen roller for supporting sheets; a flat guide member; feeding pin means cooperable with said sheets when moving relative to said guide member; a platen shifting means; means for forcing said pin means from an inoperative position through said sheets upon initial movement of said shifting means, and for advanc-

ing the same concurrently with said platen roller upon subsequent movement of said shifting means; and means for withdrawing said pin means from said sheets upon return movement of said shifting means.

7. In a device of the character described the combination of a platen roller for supporting sheets; a flat guide member; feeding pin means cooperable with said sheets when moving relative to said guide means; a platen shifting means; means for forcing said pin means from an inoperative position through said sheets upon initial movement of said shifting means, and for advancing the same concurrently with said platen roller upon subsequent movement of said shifting means; means for withdrawing said pin means from said sheets upon return movement of said shifting means; and spring means for returning said pin feeding means to the initial inoperative position.

8. In a device of the character described the combination of a platen roller for supporting sheets; a guide member; feeding pin means cooperable with said sheets when moving relative to said guide member; means for locking said sheets on said roller; means for forcing said pin means from an inoperative position through said sheets and for moving said locking means to an inoperative retracted position; means for subsequently advancing said feeding pin means conjointly with said platen roller; and means for withdrawing said pin means from said sheets and for moving said locking means into operative position at the end of the sheet advancing movement.

9. In a device of the character described the combination of a platen roller for supporting sheets; a substantially flat guide member; pin feeding means cooperable with said sheets when moving relative to said guide member; platen shifting means; means operable by said shifting means upon initial movement thereof for forcing said pin means from an inoperative position through said sheets; and clutch means for connecting said shifting means and said pin feeding means to advance the latter conjointly with the platen roller upon subsequent movement of said shifting means.

10. In a device of the character described the combination of a platen roller for supporting sheets; a guide member; pin feeding means cooperable with said sheets when moving relative to said guide member; platen shifting means; means actuated by said shifting means for forcing said pin means from an inoperative position through said sheets; a gear associated with said platen; a rack engageable with said gear for advancing said pin feeding means conjointly with said platen; and means operable by said shifting means for locking said gear and said platen for conjoint rotation subsequent to the piercing of said sheets by the pin feeding means.

11. In a device of the character described the combination of a platen roller for supporting sheets; a substantially flat guide member; a pair of feeding pins, spaced laterally of the guide member and movable toward and away from each other to cooperate with margins of divers width sheets; platen shifting means; and means operable by said shifting means for forcing said pins through said sheets and subsequently advancing the same conjointly with said platen roller.

12. In a device of the character described the combination of a platen roller for supporting sheets; a guide member; a pair of locking pins, spaced and movable laterally of the platen roller;

a pair of feeding pins spaced and movable laterally of the guide member; platen shifting means; and means operable by said shifting means for forcing said feeding pins into said sheets, for 5 moving said locking pins out of said sheets and for subsequently advancing said feeding pins conjointly with said platen roller.

13. In a device of the character described the combination of a platen roller for supporting 10 sheets; a guide member; a pair of locking pins, spaced and movable laterally of the platen roller; a pair of feeding pins spaced and movable laterally of the guide member; platen shifting means; means operable by said shifting means for forcing 15 said feeding pins into said sheets, for moving said locking pins out of said sheets and for subsequently advancing said feeding pins conjointly with said platen roller; and means for forcing said locking pins into and for drawing said feeding pins out of said sheets upon completion of said 20 platen advancing movement.

14. In a device of the character described the combination of a platen roller for supporting sheets; a guide member; platen rotating means; 25 pin feeding means movable from an inoperative position to pierce said sheets when passing the guide member; means controlled by said platen rotating means for moving said feeding means to advance said sheets; and sliding cam means controlled by said platen rotating means for positively 30 moving said feeding means into operative engagement with said sheets prior to operation of said feeding pin advancing means.

15. In a device of the character described the combination of a platen roller for supporting 35 sheets; a guide member having grooves therein extending in the direction of feed; platen rotating means; pin feeding means; and means controlled by said platen rotating means for forcing said pin means through said sheets and into said 40 grooves, and for subsequently advancing said pin means concurrently with said platen roller.

16. In a device of the character described the combination of a platen roller for supporting 45 sheets; a table member for guiding said sheets relative to said platen roller; means for normally locking said sheets relative to said platen; pin means for advancing said sheets on said table member; platen rotating means; means operable

by said rotating means for positively moving said locking means away from said platen and for forcing said pin means through said sheets; and means operable by said rotating means for subsequently advancing said pin means relative to 5 said table member concurrently with said platen roller.

17. In a device of the character described the combination of a platen roller for supporting 10 sheets; a flat guide member; platen rotating means; a control bar; pin feeding means carried by and slideable on said bar to cooperate with sheets of divers widths; and means operable by said platen rotating means for moving the control bar towards said guide member to force the 15 pin means through the sheets and for subsequently moving said bar to advance said pin means concurrently with said platen.

18. In a device of the character described the combination of a platen roller for supporting 20 sheets; a flat guide member; a platen shifting means; pin feeding means for advancing said sheets on said flat guide member; pressure means for maintaining the sheets in engagement with said platen roller and movable from a normal operative to a releasing position; means for moving said pressure means from the operative to the releasing position upon actuation of said shifting means; and means for moving said pin feeding means into operative position to advance 25 30 said sheets upon actuation of the shifting means.

19. In a device of the character described the combination of a platen roller for supporting sheets; a flat guide member; platen shifting means; pin feeding means for advancing said 35 sheets on said flat guide member; pressure means for maintaining the sheets in engagement with said platen roller and movable from a normal operative to a releasing position; a paper lock bail movable from a raised inoperative position to a 40 lowered operative position relative to said platen; means for moving said pressure means from the operative to the releasing position upon movement of said bail to its operative position; and means for moving said pin feeding means into 45 operative position to advance said sheets upon actuation of the shifting means.

BEULAH LOUISE HENRY.
